UNITED STATES PATENT OFFICE.

WILLIAM FREDERIC STIFEL, OF WHEELING, WEST VIRGINIA.

DESIGN FOR FABRIC.

SPECIFICATION forming part of Design No. 36,041, dated September 2, 1902.

Application filed August 6, 1902. Serial No. 118,684. Term of patent 7 years.

To all whom it may concern:

Be it known that I, WILLIAM FREDERIC STIFEL, a citizen of the United States, residing at Wheeling, in the county of Ohio and State of West Virginia, have invented and produced a new, original, and ornamental Design for a Fabric, of which the following is a specification.

The invention relates to a new, original, and ornamental design for a fabric; and it has for its object to provide an attractive design of that character.

The leading feature of the design resides in the design forming the subject-matter of the accompanying illustration.

The figure of the drawing is a plan view of a portion of the fabric, showing my new and ornamental design.

Referring to the drawing, 1 designates a portion of a fabric provided with figures 2, ²⁰ distinguishable from the ground or body of the fabric and arranged at intervals to form stripes.

The figure 2 consists of a circle 3 and arms 4, radiating from the circle, which forms an ²⁵ open center.

What I claim is—

The ornamental design for a fabric as herein shown and described.

In testimony that I claim the foregoing as ³⁰ my own I have hereto affixed my signature in the presence of two witnesses.

WILLIAM FREDERIC STIFEL.

Witnesses:

HENRY G. STIFEL,
D. F. EBBERT.
